United States Patent Office

Des. 185,770
Patented July 28, 1959

185,770

SETTEE

Ernst Meer, Los Angeles, Calif.

Application January 5, 1959, Serial No. 54,044

Term of patent 14 years

(Cl. D15—11)

Fig. 2

Fig. 3

Fig. 4

Figure 2 is an enlarged view of one of the ribs, the rear thereof being substantially the same as the front;

I claim:

The ornamental design for a settee, substantially as shown and described.
